UNITED STATES PATENT OFFICE

2,452,825

SINGLE TRIGGER ACTION FOR DOUBLE-BARREL SHOTGUNS

Charles A. Young, Springfield, Ohio

Application August 23, 1945, Serial No. 612,181

7 Claims. (Cl. 42—42)

1

This invention relates to improvements in firearms, and more particularly to either double barrel or single barrel shot guns and especially to means for locking the sear actuators which means is operated to unlock position by the pressure of the gun upon the shoulder of the shooter.

One of the objects of the invention is to provide a locking device of this character which can be readily installed in a conventional type gun without disturbing the firing mechanism of the gun and in which the firing mechanism or parts thereof of the gun may be readily removed without disturbing the connections which lead from the shoulder piece to the locking device.

A further object of the invention is to provide a pivoted locking device for the sear actuators of the gun which is operated from the shoulder piece and which may be readily applied to the support for the firing mechanism without disturbing the mechanism.

A further but nonetheless important object of the invention is to prevent "doubling," that is, unintentional immediate successive discharge of the second barrel of a double barreled gun, as a result of the "involuntary pull" incident to recoil and subsequent rebound of the gun upon discharge of the first barrel.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

A dominant feature of the present construction is automatic prevention of accidental discharge of the second barrel of a double barreled gun having a common finger trigger for the firing mechanism of both barrels.

Under ordinary conditions of use upon discharge there are two very definite movements of the gun. Even though the gun is being pressed tightly against the shoulder, at the moment of discharge, the resulting recoil causes further strong retractive movement against the shoulder which is immediately followed by an equally strong forward impulse or rebound.

In a gun of the character mentioned, having a single finger trigger and a switching mechanism for automatically alternating its control of the firing mechanism of the respective barrels, the recoil at the moment of discharge of the first barrel

rel to be fired causes an involuntary relaxation of finger pressure upon the finger trigger, sufficient to permit its return and effect the switch of its control to the complementary firing mechanism of the other barrel. Thereafter the rebound of the gun or forward impulse following the recoil is quite likely to exert forward pressure of the finger trigger against the shooter's finger, which he has not yet removed from firing position. It will be understood that the sequence of the initial pull upon the trigger, the discharge, recoil and rebound will have occurred almost instantaneously. The switch of influence of the finger trigger having occurred upon the recoil, the involuntary pull incident to the rebound effects discharge of the second barrel. The present construction affords a safety feature whereby such accidental discharge is positively prevented.

In the accompanying drawings:

Fig. 1 is a side elevation of a portion of a double-barrel gun partly broken away, embodying the present invention with some of the operating parts shown in dotted lines.

Fig. 2 is an enlarged side elevation of a portion of the gun partly broken away and shown in section.

Fig. 3 is an enlarged view partly in section and partly in side elevation and partly broken away of a portion of the opposite side of the gun showing the locking device for the trigger in locking position.

Fig. 4 is an enlarged view partly broken away of some of the parts shown in Fig. 3 but showing the locking device in unlocking position.

Fig. 5 is a perspective view of the trigger and the pivotal connector which connects the trigger to the opposite firing mechanism.

Fig. 6 is a side elevation partly in section and partly broken away showing the parts in a different position than that shown in Fig. 2.

Fig. 7 is a section on the line 7—7 of Fig. 6.

Like parts are indicated by similar characters of reference throughout the several views.

Referring first to Figs. 1 to 6, inclusive, and Fig. 7 of the drawings, 1 represents one of the barrels of the gun, 2 the stock and 3 the intermediate housing which encloses the firing mechanism. This housing has a removable bottom plate 4 which carries some of the parts of the firing mechanism. The plate 4 in the present case has an inverted U-shaped auxiliary support 5 which is secured thereto in any suitable manner. In Figs. 1, 2, 3, 4, 6 and 7 one of the sear actuators is indicated at 6 which is pivoted on a pin 7 which is carried by the plate 4. The plate

4 is provided on each side thereof with ears 8 through which the pin extends. The pin is in the nature of a screw which extends through one of the ears and has a threaded connection with the other ear. On the opposite side of the gun shown in Figs. 3 and 4 there is provided a sear actuator 9 which has a finger trigger 10 connected therewith, the sear actuator 9 being pivoted on the pin 7.

Pivoted to the sear actuator 9 is a connector 11, the pivotal connection being a screw 12 (Fig. 5). This connector is for the purpose of connecting under certain conditions the sear actuator 9 with the sear actuator 6. The free end of this connector 11 has a notch 13 which receives the free end of a spring 14, the intermediate portion of which is wrapped about a pin 15 screwed into the support 5 and the other end of which is extended beneath a pin 16. This spring serves under some conditions to hold the free end of the connector in contact with the forward wall of a groove 17 cut into the side of the support 5.

Normally before the gun is fired the free end of the connector 11 is held in line with a groove 18 also cut into the side of the support 5, the two grooves being separated by a wall 19. The tail 21 of a sear 20 bears on a lug 22 on the connector and serves to hold the free end of the connector in line with the groove 18 against the tension of its spring. When the connector is held in that position it is maintained in disconnected relation with the sear actuator 6. The means for connecting the connector to the sear actuator 6 consists of a lug 23 on the connector which is adapted to enter a notch 24 in the sear actuator 6 (Figs. 1, 2, 3, 6, and 7) when the connector is in line with the groove 17. When, however, the connector is being held by the tail 21 of the sear 20 in line with the groove 18 the projection 23 will be out of notch 24 in the position shown in Fig. 2 so that when the sear actuator 9 is operated the sear actuator 6 will be left unoperated. After the firing of the barrel corresponding to the sear actuator 9 a spring 25 returns the sear actuator 9 to normal position, withdrawing the free end of the connector 11 from the slot 18 and permitting its spring to throw the free end of the connector against the forward wall of the groove 17 and in line with the groove 17 so as to connect the two sear actuators so that upon pressing the finger trigger 10 the other sear actuator 6 will release its corresponding sear 26 through the medium of a projection 27 on the sear actuator 6 which lies beneath the tail of the sear 26. The impact member or hammer corresponding to the sear 20 is indicated at 28 and the impact member or hammer corresponding to the sear 26 is indicated in dotted lines at 29; a flat spring, one of which is shown in dotted lines at 29' in Fig. 2, is provided for each impact member to impel it to firing position. In the present case both impact members and the two sears are pivotally supported by the side walls of the housing 3.

Each of the sears is pressed to engaging position with relation to its corresponding impact member by a coil spring 30. The spring for the sear 20 also acts to press the tail 21 of the sear 20 upon the lug 22 of the connector 11 so as to hold the lug 23 out of operative relation with the sear actuator 6 and thereby normally maintain the two sear actuators in disconnected relation. When the finger trigger 10 is pressed to release its corresponding sear 20 the free end of the connector will ride into the slot 18 to maintain the two sear actuators in disconnected rela-

tion, but when pressure is released upon the finger trigger and the sear actuator 9 restored to its normal position by its spring 25 the connector after leaving the slot 18 will be rocked by its spring against the forward wall of the slot 17 to cause the two sear actuators to be connected by reason of the fact that the lug 23 will be projected into the notch 24 in the sear actuator 6 so that when the finger trigger 10 is again pressed the sear actuator 6 will release its sear 26 from the impact member 29 to permit the second barrel to be fired.

Provision is made for locking the sear actuator 9 until the shoulder piece of the gun is pressed against the shoulder of the shooter in the following manner: A latch 32 is pivoted intermediate its length on the support 5, the latch being received in a slot in said support with a pivot pin 33 extending through the support and latch. The lower arm of the latch is provided with a projection 34 which is normally spring pressed by a spring 35 to a position above the lug 36 on the rear end of the sear actuator 9, the spring being in the nature of a spring wire which has one end connected to the upper arm of the lever and bears against the pivot pin 33 which is extended laterally beyond the support 5 for that purpose. The lower arm of the latch also has a projection 37 which is adapted to strike the lower wall of the slotted portion of the support 5 which acts as a stop. The end of the stock of the gun has secured thereto in any well known way a shoulder piece 38 of well known construction, being preferably formed of soft vulcanized rubber or other resilient material and provided with a chamber 39 which opens to the end of the stock. The stock of the gun is formed with a bore 40 through which extends a rod 41. The rear end of this rod 41 is inserted in a slot in a boss 42 secured to and projecting from a plate 43 by the pivot pin 44 and a coil spring 45 located in a thimble 46 embedded in the stock and interposed between the outer end of the thimble and the boss serves to press the plate against the rear wall of the chamber 39 and hold the rod in inoperative position so long as no pressure is placed upon the shoulder piece. The forward end of the rod 41 has secured thereto in any suitable way an enlarged member 47 which snugly fits the extreme forward end of the bore 40 and projects into the housing 3 where it is provided with a projection 48 which stands in operative relation with the latch 32. The projection 34 of the latch 32 normally lies above the projection 36 on the sear actuator 9 so as to lock the sear actuator, but when pressure is applied to the shoulder piece by pressing the gun against the shoulder of the shooter the rod 41 will be projected forwardly so as to rock the latch 32 to cause its projection 34 to move to the position shown in Fig. 4 to unlock the sear actuator 9 so that one barrel of the gun may be fired. As soon as pressure is relieved on the trigger and on the shoulder piece the sear actuator will be forced back to its normal position and the locking projection of the lever 32 again restored to locking position by its spring.

By this construction, the locking device described may be readily installed upon any existing gun of the character referred to, as the only thing necessary is to remove the bottom plate 4 which carries a portion of the firing mechanism, slot the rear end of the support 5 to receive the locking latch 32 and bore the stock 2 to receive the operating rod 41 and its associated parts. When it is necessary to remove the firing mechanism car-

ried by the plate 4 this can be readily accomplished without disturbing in any way the operating rod 41 and its associated parts including the resilient shoulder piece, inasmuch as the forward end of the rod is free of the support.

In the present instance, the momentary release of finger pressure incident to the recoil which enables automatic switch of the influence of the finger pull trigger 10, also enables simultaneous locking engagement of the detent 32 over the tail 36 of the trigger 9. This occurs upon the involuntary release of the finger trigger 10 upon the retractive recoil and before the forward rebound by which the trigger would otherwise be again pulled to fire the second barrel.

If it was possible to hold the finger trigger 10 retracted as shown in Fig. 4, after the moment of discharge, the detent could not engage over the tail 36 of the finger pull but neither would the switch of influence to the second barrel firing mechanism have then occurred, which can only occur upon release of the finger trigger and its return to the Fig. 3 position. However, the finger trigger cannot be so held in operated position because the recoil of the gun moves the finger trigger rearwardly from the shooter's finger and effects involuntary release of pressure thereon. Whereupon the finger trigger returns to normal and switches its influence to the second barrel firing mechanism. As pressure against the shoulder is relaxed the detent 32 automatically locks the finger trigger before the rebound acquires momentum and before the moment of involuntary pull upon the finger trigger 10 as result of the rebound, the finger trigger has been already locked by the detent, and can only be unlocked preparatory to intentional firing of the second barrel by a firm pull of the gun stock against the shooter's shoulder, by which the plunger 41 is actuated as before described to rock the detent 32 out of its locking position.

Thus a pulling influence upon the gun stock against the shoulder is compulsory to unlock the finger trigger preparatory to firing each barrel and the finger trigger is automatically locked after the first barrel is discharged before the second barrel may be accidentally discharged by involuntary pull on the finger trigger 10.

The present application is a continuation in part of original application Serial No. 342,007, filed June 24, 1940, now matured into Letters Patent No. 2,401,034, issued May 28, 1946.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. Dual firing mechanism for a double barreled firearm, wherein separate impact members, one

for each barrel, are independently held cocked by separate sears independently releasable by separate sear actuators, including a single finger trigger common to both firing mechanisms carried

5 by one of the sear actuators, a coupler pivotally mounted on the same sear actuator by which the finger trigger is carried, having operative relation with the sear of one impact member movable into operative engagement with the sear of the other impact member by oscillatory adjustment of the pivoted coupler, and a stationary guide member with which the pivoted coupler is engageable in its alternate positions of oscillatory adjustment.

10 2. Dual firing mechanism for a double barreled firearm, wherein independently releasable impact members are held cocked by separate sears, disengageable therefrom by independent sear actuators including a single finger trigger carried by one sear actuator and common to both firing mechanisms, an oscillatory coupler carried by the same sear actuator by which the finger trigger is carried, automatically operative upon return motion of said sear actuator from disengagement of the corresponding sear from its impact member 15 to assume relation to the second sear for disengagement of the second sear from its impact member upon subsequent movement of the same sear actuator by the common finger trigger.

20 3. Dual firing mechanism for a double barreled firearm, wherein independently releasable impact members are held cocked by separate sears, disengageable therefrom by independent sear actuators including a single finger trigger carried by one sear actuator and common to both firing mechanisms, 25 an oscillatory spring influenced coupler carried by one of the sear actuators, and automatically movable into interlocking engagement with the other sear actuator upon return motion of the first sear actuator from operative action in disengaging one of the sears to release its corresponding impact member, a guide for said oscillatory coupler directing it into operative relation with the other sear actuator to disengage the corresponding other sear upon succeeding operation of the first sear actuator by said common finger trigger.

30 4. Dual firing mechanism for a double barreled firearm, wherein independently releasable impact members are held cocked by separate sears, disengageable therefrom by independent sear actuators including a single finger trigger carried by one sear actuator and common to both firing mechanisms, a relatively movable spring influenced coupler carried by one of the sear actuators and automatically movable into interlocking engagement with the second sear actuator upon return motion of the initial sear actuator from disengagement of its corresponding sear to release the related impact member.

35 5. Dual firing mechanism for a double barreled firearm, wherein independently releasable impact members are held cocked by separate sears, disengageable therefrom by independent sear actuators including a single finger trigger carried by one sear actuator and common to both firing mechanisms, a pivotally mounted coupler carried by the finger trigger carrying sear actuator normally engageable with the corresponding sear to release the related impact member upon movement of the sear actuator under influence of the common finger trigger, and automatically engageable with the second sear actuator to disengage the second sear to release its related impact member upon repetition of the finger trigger influence upon the first trigger.

6. Dual firing mechanism for a double barreled firearm, wherein independently releasable impact members are held cocked by separate sears, disengageable therefrom by independent sear actuators including a single finger trigger carried by one sear actuator and common to both firing mechanisms, including a finger trigger common to both firing mechanisms carried by one of the sear actuators, a coupler carried by the same sear actuator and automatically movable into interlocking engagement with the other sear actuator upon return movement of the first sear actuator from having disengaged its corresponding sear to release its related impact member preparatory to unison movement of both sear actuators under influence of a succeeding retraction of the common finger trigger to disengage the other sear from its related impact member.

7. Dual firing mechanism for a double barreled firearm, wherein independently releasable impact members are held cocked by separate sears, disengageable therefrom by independent sear actuators including a single finger trigger carried by one sear actuator and common to both firing mechanisms, an oscillatory coupler pivoted to the same sear actuator, oppositely extending off-

set lugs projecting from the coupler, one of which is engageable with the sear corresponding to said sear actuator to disengage the sear from its related impact member upon movement of the sear actuator by retraction of the finger trigger, the other of which lugs is engageable with the second sear actuator upon return motion of the first sear actuator after having disengaged the corresponding sear, a spring for shifting the coupler, and a stop preventing shift of the coupler under influence of the spring prior to complete return of the operated sear actuator preparatory to oscillation of the coupler into engagement with the second sear actuator for disengagement of the second sear upon subsequent unison operation of the sear actuators.
